7 Claims. (Cl. 137—117)

This invention relates to hydraulic control valves and more particularly to hydraulic control valves of the spool type.

Systems heretofore known in which a fluid flow is supplied through a hydraulic control valve have usually suffered from the disadvantages that in cases where the full fixed flow rate supplied is greater than the requirements, the supply has to be effected via additional flow regulating valves outside the control valve or via a control spool having a restricted waist or holes, and such systems are not only complicated to construct and install but systems using a control spool with a restricted waist or holes are wasteful to operate on account of the unnecessary pressure to which the fluid must be raised.

The present invention has for its main objective to overcome these disadvantages and the invention accordingly consists in a hydraulic control valve comprising a valve body having a bore therethrough, at least one service port and a high and a low pressure port in communication with said bore, a control spool having a passage therethrough slidably engaged in said bore and provided with service control ports therein at one end and constructed and arranged so that in one position of said spool, communication is established between the service port and the low pressure port through said passage and is precluded between the high pressure port and said passage, and in another position thereof communication is established between the service port and the high pressure port through said passage and is precluded between the low pressure port and the passage, said spool having by-pass port means establishing communication between said low pressure port and said passage and spaced from said end having the service control ports therein, a valve seat in said passage between said service control ports and said by-pass port means, an elongated by-pass valve member in said passage adapted to co-operate with said seat and constructed and arranged so that a predetermined flow rate is maintained from said high pressure port through said passage to said service port when said spool is in said another position, means biasing said valve member to a closed position on said seat, said valve being pressure balanced at its opposite ends and responsive to pressure from said high pressure port when said spool is in said another position to move from said seat against the force of the biasing means, whereby pressure in excess of a predetermined amount is by-passed to said by-pass port.

The invention also consists in a hydraulic control valve comprising a valve body having a bore therethrough, at least one service port and a high and a low pressure port in communication with said bore, a control spool having a passage therethrough slidably engaged in said bore and provided with service control ports therein at one end and constructed and arranged so that in one position of said spool, communication is established between the service port and the low pressure port through said passage and is precluded between the high pressure port and said passage, and in another position thereof communication is established between the service port and the high pressure port through said passage and is precluded between the low pressure port and the passage, said spool having by-pass port means establishing communication

2

between said low pressure port and said passage and spaced from said end having the service control ports therein, dual valve seats in said passage between said service control ports and said by-pass port means, dual elongated by-pass valve members in said passage adapted to co-operate with said seats and constructed and arranged so that a predetermined flow rate is maintained from said high pressure port through said passage to said service port when said spool is in said another position, means biasing said valve members to a closed position on said seats, said valve being pressure balanced at its opposite ends and responsive to pressure from said high pressure port when said spool is in said another position to move from said seat against the force of the biasing means, whereby pressure in excess of a predetermined amount is by-passed to said by-pass port.

The invention will be more completely understood from the following detailed description which is given in conjunction with the accompanying drawing which shows a sectional side view of a spool type hydraulic control valve constructed in accordance with the invention.

Referring now to this drawing 1 is the main casing in the bore of which the control spool 2 of an open centre parallel circuit hydraulic control valve is slidably mounted, this spool being provided with two flow control valves 3, 3', one for each service. With the main control spool 2 in the neutral position, the fluid supply is passed to the low pressure return gallery 5 of the valve via the central waist 6 of the main control spool. Movement of the control spool 2 in either direction will then shut off the escape of oil via the waist 6 of the main control spool and will raise the pressure in the galleries 7 and 8. If the main control spool is now moved in to the housing, that is to say, from left to right in the drawing, one service control port 10 will be connected to the high pressure gallery 7 and the other service port 9 to the low pressure gallery 5. If however, the plunger and control spool are moved in the opposite direction, the second service port 9 will be connected to the high pressure gallery 8 and the first service port 10 will be connected to the low pressure gallery 5. The flow control valves 3 and 3' for the two services take the form of elongated by-pass valve members comprising flow control plungers which are slidably disposed in the bore of the spool 2. Each of these plungers is arranged to seat against a tubular stop 11 which seats in an internal seat 12 cut into the spool at one end, and is guided by a sleeve 13 located in the spool at the other end, and the plunger is urged towards the stop 11 by a helical spring 14 mounted between the sleeve 13, and a shoulder 15 on the plunger, a central passage 16 being formed through the plunger to balance pressure between the ends. For any particular direction of movement, the flow control plunger associated with the service port 9 or 10 to be connected with a high pressure gallery 7 or 8 will be supplied with fluid through the high pressure spool port 17 to the space 18. The flow then passes from this space via an annular clearance 19 or through slots in the plunger land to the space 20, whence it escapes via the low pressure spool port 22 to the service port 9 or 10. The passage of fluid via the clearance space 19 causes a pressure drop across the plunger land thus providing a force to compress the return spring 14. This allows part of the flow to by-pass at the internal seat of the valve and the by-pass flow makes its exit into the low pressure gallery 5 via the ports 21.

An alteration of the service condition such as would tend to allow the flow to increase will cause a greater pressure drop to occur through the clearance 19 and this would result in a greater compression of the return spring 14. This in turn will allow a greater area to be opened to the by-pass flow and the controlled flow will consequently be reduced. Conversely a condition tending to

reduce the flow from the service port will reduce the pressure drop through the clearance 19 thus allowing the spring to extend further so as to shut off the by-pass flow area and increase the controlled flow. The flow control valve is therefore self-regulating and pressure compensating.

The provision of by-pass flow regulators of the type hereinbefore described does not impair the inching characteristics of the control spool. As the neutral circulation galleries are cut off in favour of the supply to the high pressure galleries 7 and 8, the ports 17 and 22 are opened progressively thus allowing the flow to increase up to the flow setting of the regulator before the by-pass area at the seat end of the flow regulator unit begins to open. Consequently, the initial control is effected by means of throttling on the control spool ports.

When one end of the control spool 2 is selected to supply a service port, the other end selects the connection of the other service port to the low pressure gallery 5. Under this condition fluid from one service port 10 enters the spool holes 17 into the space 18 and the flow passes from the space 18 via the clearance 19, space 20, and holes 22 into the low pressure gallery 5. The flow control valve operates as before, passing a controlled portion of the flow to the low pressure gallery via the holes 22 in the spool, and passing the surplus flow via the seat opening at the other end of the flow control plunger. Under this condition the correct proportion of the flow is normally a matter of indifference.

It is to be understood that the control spool shown may be one of a number of such spools containing flow regulating valves, all of which may be mounted in the common casing 1, so as to communicate with common sources of high and low pressure, the spools being conveniently disposed parallel to one another, and arranged in a manner similar to that shown in the drawing.

I claim:

1. Hydraulic control valve comprising a valve body having a bore therethrough, at least one service port and a high and a low pressure port in communication with said bore, a control spool having a passage therethrough slidably engaged in said bore and provided with service control ports therein at one end and constructed and arranged so that one position of said spool, communication is established between the service port and the low pressure port through said passage and is precluded between the high pressure port and said passage, and in another position thereof communication is established between the service port and the high pressure port through said passage and is precluded between the low pressure port and the passage, said spool having by-pass port means establishing communication between said low pressure port and said passage and spaced from said end having the service control ports therein, a valve seat in said passage between said service control ports and said by-pass port means, an elongated by-pass valve member in said passage adapted to co-operate with said seat and constructed and arranged so that a predetermined flow rate is maintained from said high pressure port through said passage to said service port when said spool is in said another position, means biasing said valve member to a closed position on said seat, said valve being pressure balanced at its opposite ends and responsive to pressure from said high pressure port when said spool is in said another position to move from said seat against the force of the biasing means, whereby pressure in excess of a predetermined amount is by-passed to said by-pass port.

2. A hydraulic control valve comprising a valve body having a bore therethrough, at least one service port and a high and a low pressure port in communication with said bore, a control spool having a passage therethrough slidably engaged in said bore and provided with service control ports therein at one end and constructed and arranged so that in one position of said spool, communication is established between the service port and the low pressure port through said passage and is precluded between the high pressure port and said passage, and in another position thereof communication is established between the service port and the high pressure port through said passage and is precluded between the low pressure port and the passage, said spool having by-pass port means establishing communication between said low pressure port and said passage and spaced from said end having the service control ports therein, dual valve seats in said passage between said service control ports and said by-pass port means, dual elongated by-pass valve members in said passage adapted to co-operate with said seats and constructed and arranged so that a predetermined flow rate is maintained from said high pressure port through said passage to said service port when said spool is in said another position, means biasing said valve members to a closed position on said seats, said valve being pressure balanced at its opposite ends and responsive to pressure from said high pressure port when said spool is in said another position to move from said seat against the force of the biasing means, whereby pressure in excess of a predetermined amount is by-passed to said by-pass port.

3. Hydraulic control valve as claimed in claim 2, wherein each of said by-pass flow regulators comprises an auxiliary plunger slidably arranged within the passage of said control spool, each of said auxiliary plungers being guided at the other end of said passage by a sleeve located within said control spool.

4. Hydraulic control valve as claimed in claim 3, and comprising spring means for urging each of said plungers towards said seat, said spring means comprising a helical spring surrounding the plunger body and being compressed between a circumferential shoulder on said plunger and a tubular stop formed in the bore of said control spool.

5. Hydraulic control valve as claimed in claim 3, wherein each of said plungers has a centrally disposed hole extending longitudinally therethrough for ensuring pressure balance between the ends of the plungers.

6. Hydraulic control valve as claimed in claim 4, and comprising an annular restricted clearance space between said shoulder and the internal wall of said control spool for accommodating the controlled flow of fluid, and whereby a pressure loss is caused, thus energising the flow control plungers.

7. Hydraulic control valve as claimed in claim 4, wherein each said plunger has at least one slot or passage in its land for accommodating the control flow fluid, and whereby a pressure loss is caused, thus energising the flow control plungers.
